FOOD TRAY

Robert Daenen, Brembodegem, Belgium, assignor to Dart Industries, Inc., Los Angeles, Calif., a corporation of Delaware

Filed Feb. 25, 1970, Ser. No. 21,617

Term of patent 14 years

Int. Cl. D7—99

U.S. Cl. D44—10

FIG. 1 is a perspective view of a food tray showing my new design;

FIG. 2 is a perspective view thereof in inverted position;

FIG. 3 is an elevational end view;

FIG. 4 is an elevational front view; and

FIG. 5 is a cross-sectional view taken on line 5—5 of FIG. 1.

I claim:

The ornamental design for a food tray, substantially as shown.
